UNITED STATES PATENT OFFICE.

JAMES G. BLUNT, OF SCHENECTADY, NEW YORK.

LOCOMOTIVE DRAW-BAR.

1,293,315.

Specification of Letters Patent.

Patented Feb. 4, 1919.

Application filed November 11, 1918. Serial No. 262,012.

To all whom it may concern:

Be it known that I, JAMES G. BLUNT, of Schenectady, in the county of Schenectady and State of New York, have invented a certain new and useful Improvement in Locomotive Draw-Bars, of which improvement the following is a specification.

My invention relates to means for detachably connecting railroad vehicles, more particularly locomotive engines and their tenders, and its object is to provide means, of simple and inexpensive construction and ready applicability in standard construction, whereby the accidental and undesired separation of two coupled vehicles will be prevented in the event of the breakage of any essential element of the connecting device.

The improvement claimed is hereinafter fully set forth.

In the accompanying drawing: Figure 1 is a view, partly in plan and partly in horizontal section, of a locomotive draw bar device embodying my invention, and; Fig. 2, a vertical longitudinal section through the same, on the line $\alpha - \alpha$ of Fig. 1.

In the practice of my invention, referring descriptively to the specific embodiment thereof which is herein exemplified, a locomotive and tender are connected by a duplex draw bar, comprising two draw bar members, 1, 1^a, which are disposed, parallel one with the other, in the same horizontal plane and as closely together as is permissible under their transverse dimensions. The draw bar members, 1, 1^a, are coupled, at their rear ends, by pins 4, 4^a, respectively to the draw bar pin casting 5, of the tender, and their front ends are coupled, by pins, 2, 2^a, respectively, to an equalizer, 6, of disk form, which is fitted, with the capacity of movement about its axis, and slight longitudinal movement, in a draw casting, 3, formed integral with, or rigidly secured to, the foot plate of the locomotive. The equalizer, 6, normally bears, on the rear side of its transverse diametral line, on the draw casting, 3.

The equalizer 6, bears, at the forward end of its longitudinal diametral line, on a transverse buffer plate, 7, fitted, with the capacity of a slight degree of movement in line longitudinally with the locomotive, in the forward end of the draw casting, 3, thereof. The buffer plate, 7, is pressed up

to the equalizer by buffer springs, 7^a, and maintained in line longitudinally, and limited in its traverse, by bolts, 7^b, which are secured to it and pass freely through the rear end of the draw casting, 3, said bolts carrying adjustable stop nuts, 7^c. The chafing blocks, 8, of the locomotive, and, 9, of the tender, normally stand at a slight distance, as, say, about half an inch, apart, the clearance space thus provided, being designed to eliminate practically all frictional wear on the chafing blocks. The latter are designed to be brought into temporary contact, before the buffer plate, 7, has been forced by the buffing strain acting on the springs, 7^a, to the limit of its traverse toward the forward end of the locomotive. The chafing block of one of the vehicles, as the tender, may, if desired, be formed in two sections, the outer of which forms a secondary buffer plate, which is subject to outward pressure up to the clearance limit between it and the chafing block of the locomotive, by springs, 9^a, in order to resist closure of the clearance space, the parts being so designed that the clearance space between the buffer blocks is taken up and the springs, 9^a, reach the limit of their rearward traverse just before the buffer plate, 7, and springs, 7^a, reach the limit of their forward traverse. The draw bars are thereby relieved from buffing shocks due to the unyielding resistance of solid springs.

It will be seen that while the propelled vehicle or vehicles is or are drawn by the propelling vehicle, the strain of traction is applied to, and equally divided between, the two members, 1, 1^a, of the duplicate draw bar. Relative lateral movement of the coupled vehicles, in traversing curves, is provided for by the capacity of movement, about its axis, of the equalizer, 6, such movement being properly limited by stop arms, 6^a, projecting laterally from the equalizer and adapted to abut against bearing faces on the draw casting.

It will also be observed that, by reason of the form and the mounting of the equalizer, and the manner in which strain is transmitted, through it, to the duplicate draw bar members, it is subjected only to compressive strain which it can fully sustain, and is exempt from the tensile strains which are imposed upon a double armed

pivoted equalizing beam, when acting as a member for the transmission of tractive force.

By the division and equalization of the application of strain to two connecting members, as effected in the operation of my invention, each member functions both as a main and a safety draw bar, and in the event of the breakage of either of them, the vehicles will remain connected by the other, and their separation will therefore be prevented.

The improved draft appliance above described, is readily applicable, without substantial expense, in ordinary practice, and as herein illustrated, occupies but little space below the floor levels of the coupled vehicles. The difference in height between the draw bar members and the articulated water connections between the engine and tender, shown in Fig. 2, indicates the ample clearance allowable below the former.

I claim as my invention and desire to secure by Letters Patent:

1. In a railroad vehicle draft gear, the combination of two draw bar castings, each adapted to be supported upon a railroad vehicle; an equalizer disk, fitted to move both axially and longitudinally in one of said draw bar castings; a duplicate draw bar, the members of which are coupled to the equalizer disk, on opposite sides of its

axis; and connections, each coupling one of the draw bar members to the other draw bar casting.

35

2. In a railroad vehicle draft gear, the combination of two draw bar castings, each adapted to be supported upon a railroad vehicle; an equalizer disk, fitted to move both axially and longitudinally in one of said draw bar castings; a spring buffer opposing longitudinal movement of said equalizer disk; a duplicate draw bar, the members of which are coupled to said equalizer disk, on opposite sides of its axis; 45 and connections, each coupling one of the draw bar members to the other draw bar casting.

3. In a railroad vehicle draft gear, the combination of two draw bar castings, each 50 adapted to be supported on a railroad vehicle; an equalizer disk, fitted to move both axially and longitudinally in one of said draw bar castings; means for limiting the axial movements of said equalizer disk; a 55 duplicate draw bar, the members of which are coupled to the equalizer disk, on opposite sides of its axis; and connections, each coupling one of the draw bar members to the other draw bar casting.

JAMES G. BLUNT.
